SIMULATED EXPLOSIVE AMUSEMENT DEVICE

Edouard M. Sire, New York, N. Y.

Application August 15, 1951, Serial No. 241,969

4 Claims. (Cl. 46—175)

1

This invention relates to a simulated explosive device which may also serve as a container which dispenses its contents upon the apparent explosion.

As far as I am aware explosive devices have been known wherein the operation dispensed edible objects or novelties such as is described in the instant application. I am further aware that containers have been known which effect a violent dispensation of the contents as by a spring action. However, such types of devices as have been mentioned have not met with wide approval for various reasons. Probably a most compelling reason has been the danger involved in employing an explosive in a device which is attractive to children. Undoubtedly, many laws have been passed to discourage the sale of such devices. On the other hand, a device which does not incorporate some type of explosive effect has far less appeal.

Bearing the foregoing in mind I have devised an article which may take the appearance of a fire cracker or a large candle and which is lit just as is a conventional fire cracker or candle. In furthering the illusion, the device actually provides an explosive report which, however, is completely harmless, the device containing no explosive material of any sort. The device is so constructed that it falls apart simultaneously with the report and means are further provided, if desired, to eject a quantity of objects or novelties such as candy drops or party favors.

The invention will further be understood from the following description and drawings in which:

Figure 1 is a longitudinal cross-sectional view of an article made according to the instant invention and illustrating the lighting thereof;

Figure 2 is a view similar to Figure 1 but showing the effect of the explosive report and the consequent disassembly of the article;

Figure 3 is a longitudinal cross-sectional view taken along the lines 3—3 of Figure 1;

Figure 4 is a top plan view of the device before use;

Figure 5 is a bottom plan view partly broken away; and

Figure 6 is a transverse cross-sectional view taken along the lines 6—6 of Figure 1.

The article comprises a tubular container 10 having a thin decorative paper wrapper 11. A cup 12 is disposed within the wrapper 11 and is seated atop tube 10.

Wrapper 11 extends above cup 12 and below tube 10 so as to form upper and lower shoulders. Against the upper shoulder formed by the top rim of cup 12 is disposed cap 13 which is provided with an outer paper covering 14. Against the lower shoulder formed by the lower edge of tube 10 is provided base 15 having an outer paper wrapper 16. Cap 13 and base 15 are unconnected to either tube 10 or its wrapper 11 except through the action of the noise making device which will be hereinafter described. The tube

2

10, cup 12 and cap 13 may be of cardboard material but the base 15 should be of a more solid material such as wood in order to provide a loud report as will be hereinafter made clear.

5 Within the cup, and extending therethrough, is a funnel-shaped member 17 which rests mouth downward on the floor of cup 12. Such floor is provided with an opening 18 which is covered by the mouth of the funnel 17. The constricted end 10 of the funnel is formed with a pair of diametrically opposite shoulders 20 in order to support a part of the noise maker as will be hereinafter described. Surrounding the funnel is a quantity of candy 21 such as fruit drops or other 15 edible material.

The explosion or report producing member comprises a spring member in the form of rubber band 22, one end of which embraces the base 15 by extending through a bottom slot formed 20 therein. Two diametrically opposite slots 15a are formed in the base 15 in order to permit the band to embrace the base without protruding therefrom. Of course, other types of spring members may be used.

25 The rubber band 22 has its other end connected to a striker 23 which, for the present purposes, takes the form of a metal piece having hook ends. The lower hook end connects to the upper end of band 22 while the upper hook end 30 has a cord 24 tied thereto. Cord 24 is tied with a knot around pin 25 and continues so as to form a wick 26. Pin 25 is held in the top shoulders 20 of the funnel 17 so as to maintain the entire article in assembled relationship. Pin 25 may be 35 of thermoplastic material such as cellulose acetate although it may be of wood as will herein-after be described.

40 It will be noted from the foregoing that all the elements of the device are maintained assembled because the pin 25 is held at the top of the funnel. This has the effect of pulling up the base 15 through the action of the band 22 while further maintaining the cup 12 in place. The cap or cover 13 has a central opening which maintains a frictional fit with the restricted end of funnel 17 so that it too is maintained in position by the action of the taut rubber band. It will be understood that the rubber band 22 is stretched to a considerable degree when in the position shown in Figures 1 and 3.

45 A suggested way of assembling the device is to tie the cord 24 to the upper end of the striker, hook the other end of the striker around the rubber band and pull the striker upwardly by the cord until its upper hook rests over the outer edge of the restricted portion of the funnel. At this time, the cord can be tied with facility around the pin 25. The striker may then be released and permitted to descend until the pin 25 fits in the shoulders 20. It is suggested to coat the wick 26 with ordinary tallow or candle wax so that it will support adequate combustion as will hereinafter be described. However, the wick may

be impermeated with so-called sparkler material as used in pyrotechnic devices such as sparklers or fire crackers.

The device will then be assembled as illustrated in Figures 1 and 3. It thus has the appearance of a conventional fire cracker. In using the device, one applies a match to the wick 26 so as to cause it to burn down to the pin 25. As soon as it burns down to the pin, the pin softens and bends through the effect of the heat and is thus released from the shoulders 20. This releases the cord 24 from its anchored position and the striker 23 descends with great force through the contraction of the resilient band 22 and strikes the base 15 a resounding blow. Of course, the user or any spectators may have no knowledge that the report is percussive rather than explosive. The report is particularly violent if the device is disposed on a hard surface.

The action of the noise maker is further such as to effect disassembly of substantially the entire device. Thus, the funnel 17 together with cap 13, having been held only in the cup 12 by the action of the noise maker, tends to fly outwardly together with the contents 21 of the cup. At the same time, the base 15 falls away. It will be understood that the funnel shape of member 17 is instrumental in ejecting the candy objects 21 as the funnel is caused to fly outwardly. The funnel 17 does not fly outwardly to a great distance, but, probably due to the resilient inherency of cardboard cup 12, it is cocked by the rubber band 22 and tends to fly outwardly when the band is released through the action described.

It will be understood from the foregoing that a device is provided which looks and is operated just as is a fire cracker or a candle which may find use in parties or gatherings. Its operation is accompanied by an explosive report. Such report effectively disassembles the device thus amplifying the effect of the explosion. However, notwithstanding the realism and amusement value of the device, it involves no danger in its operation.

Pin 25 may also be of wood or the like since it has been found that a wooden pin burns satisfactorily and consumes the knot so as to release the cord from the pin and achieve the desired report.

It will be further understood that the body, cap and base may be of plastic material instead of cardboard, paper or wood as described save that such substitution may increase the expense of the device.

What is claimed is:

1. An article of the character described comprising a tubular, hollow body, a base enclosing one end of said body, a spring member anchored to said base, a striker connected to said spring member, a cord connected to said striker, anchorage means on said cord for maintaining it in an upward position so that the striker is also maintained upwardly and the spring member is maintained in an extended position, said cord extending past said anchorage means so as to serve as a wick, burning of said wick destroying said anchorage means to release the cord and contract the spring member so that the striker descends forcefully to strike said base.

2. An article according to claim 1 and wherein said anchorage means comprises a knot tied in said cord, a thermoplastic pin around which the knot is tied, said pin being normally straight and supported adjacent the upper end of the

body, heating of said pin softening it and causing it to collapse from its support so as to release said cord, said spring member being an endless rubber band and said striker being a metal object having two hooked ends, one of said ends embracing the rubber band and the other hooked end having said cord tied thereto, said cap and base being held to said body by the action of the extended or taut rubber band whereby the contraction thereof releases the cap and base from the body.

3. An article of the character described comprising a hollow body, a resiliently expansive and contractable member anchored at one portion thereof adjacent one end of said body, a striker connected to an opposite portion of said member, and holding means connected to said striker for maintaining said member in expanded condition, said holding means including a heat responsive member which is anchored at the other end of said body, said heat responsive member being responsive to heat applied thereto for releasing said holding means from its anchored position at said other end of the body so as to release said striker and cause it to be forcefully propelled by said member toward said one end of said body, and a sounding member maintained within said body at said one end thereof so as to be in the path of movement of said striker when it is propelled upon the release of said holding means.

4. An article of the character described comprising a tubular hollow body, a resiliently expansive and contractable member normally maintained taut in said body, a striker connected to said member for maintaining it taut, a cord connected to said striker and pulling it upwardly in maintaining said member taut, said cord being anchored adjacent the upper end of said body, said cord extending further than the anchorage thereof, said cord being combustible whereby lighting of said further extending end burns said anchorage so as to release said striker and effect a violent downward propulsion thereof by said member, a base for said body which is embraced by said member and which is struck by said striker when it is downwardly propelled, said member comprising an elastic rubber band, said base being formed with a groove into which said band is received, said striker being of metal, a pin about which said cord is tied to form its anchorage, a cup in the upper part of said body said cup being formed with a shoulder for holding said pin and maintaining it in an upper position against the action of said rubber band, said cup being formed with a central opening in its floor through which said cord extends, an inverted funnel member disposed with its mouth over said opening, said cup being filled with contents to be dispensed and disposed around said funnel member.
